E. NELSON

CONSTRUCTION FOR GAS PRODUCERS

Filed Aug. 28, 1924

Patented Aug. 25, 1925.

1,551,422

UNITED STATES PATENT OFFICE.

EDWARD NELSON, OF NEW YORK, N. Y.

CONSTRUCTION FOR GAS PRODUCERS.

Application filed August 28, 1924. Serial No. 734,787.

To all whom it may concern:

Be it known that I, EDWARD NELSON, a citizen of the United States, and a resident of the city of New York, borough of Manhattan, in the county and State of New York, have invented a new and Improved Construction for Gas Producers, of which the following is a full, clear, and exact description.

10 The present invention relates to new and useful improvements in gas-producing furnaces, and it pertains more particularly to a new and improved mechanism for operating the purge cap thereof.

15 In the general type of construction heretofore employed, the purge-cap carrying element is supported by a framework independent of the furnace body. This construction, owing to the warping of the furnace, moves the same out of register with the purge-cap opening and leaves a space through which gas escapes.

It is one of the primary objects of the present invention to provide means whereby 25 the purge cap is carried by a truck, the supports of which are carried by the furnace itself in such a manner that should the furnace warp, the purge cap will not be thrown out of register with the furnace but will be carried therewith to its warped position.

It is a further object of the invention to provide a stationary track and a movable track, the latter serving to lift the truck in order to permit of its rolling along the 35 stationary track.

It is a further object of the invention to provide means by which the movable track and the purge-cap carrying truck are operated in properly timed relation.

40 With the above and other objects in view, reference is had to the accompanying drawings, in which—

Figure 1 is a top plan view of the mechanism constructed in accordance with the present invention;

Fig. 2 is a view thereof in side elevation;

Fig. 3 is a detail sectional view taken on the line 3—3 of Fig. 2;

Fig. 4 is a detail vertical sectional view 50 taken on the line 4—4 of Fig. 2.

Referring more particularly to the drawings, the reference numeral 10 designates the upper portion of a gas-producing furnace, and such furnace has a tapered upper end

designated by the reference numeral 11. 55 This upper end is adapted to be closed by a purge cap 12, which purge cap is mounted on wheels or the like, 13. These wheels are adapted to roll upon two stationary track members 14, and, as more clearly shown in 60 Figs. 1 and 4, these stationary track members 14 are secured to the upper end of the furnace 10, by means of bolts, rivets, or the like, 15. As more clearly shown in Fig. 1, there are two of these tracks, one 65 at each side of the furnace, and each of these tracks is provided on its outer face with guide lugs, or the like, 16. Suitably mounted between these guide lugs 16 and its respective stationary track 14, there is a 70 movable track 17, and these tracks 17 are each narrower than its respective stationary track 14. Mounted in brackets carried by each of the stationary tracks 14, there are rollers 18, and the movable tracks 17 heretofore referred to are adapted to roll thereon. Each of these movable tracks 17 is 75 notched at each end, as at 19, and such notches are adapted to receive the rollers 18 to permit of the lowering of the movable 80 tracks 17.

When the purge cap is set in position, the wheels 13 of the truck are adapted to be received within recesses 20 to prevent any accidental movement of the truck relative 85 to the stationary tracks.

The reference numeral 30 designates a hydraulic cylinder of suitable design, and the piston 31 thereof is connected to the crank 32, which in turn operates a shaft 90 33. Connected to a crank 34 carried by the shaft 36, there is a lever 35, and such lever is connected, as at 36', to a bell crank lever 37', which in turn is connected as at 38' to a lever 39' connected to the movable 95 track 17. There are preferably two of these mechanisms, there being one at each side of the track.

* The reference numeral 37 designates a lever pivotally connected, as at 38, to a lever 39, which in turn is connected to the truck, as at 40, it being understood that there are two of these mechanisms, one adjacent each track member, a shaft 33 heretofore mentioned being mounted in suitable bearings 100 40 carried by a frame structure 41 supported in any desired manner.

At one end of the frame there is a trans-

versely extending bar or brace 42, and such bar or brace carries a bumper 43, with which the door-carrying truck is adapted to engage when the truck is moved to position 5 to close the door.

The device operates in the following manner:

With the parts in the position shown in Fig. 2, the purge cap is shown in its closed 10 position. When it is desired to open the door, the hydraulic cylinder is operated to rock the shaft 33, and through the medium of the lever 35 the movable tracks 17 are reciprocated beneath the wheels 13 until the 15 lowermost surfaces of said tracks 17 ride up, respectively, on the rollers 18. This elevates the movable tracks 17 and lifts the wheels 13 out of their respective notches 20. This lifting of the wheels 13 out of 20 their respective notches 20, elevates the truck and lifts the charging opening cover from the charging opening of the producer furnace 10. At this point the lever 37 operates upon the lever 39 and reciprocates 25 or moves the truck along the stationary tracks 14 carrying the purge cap with it, and leaving the purge-cap opening exposed.

After the furnace has been purged, the 30 hydraulic cylinder 30 is again operated to move the truck in position over the furnace, and after the tracks 17 have been lowered, the purge cap will be lowered into position by reason of the wheels 13 passing into their respective notches 20 and the 35 purge cap will be securely retained in closed position.

From the foregoing it is apparent that 40 should the furnace 10 warp or become distorted during this operation, owing to the fact that the several tracks are carried by the upper end thereof, they travel therewith and any warping would not tend to leave an opening around the purge cap through 45 which gases could escape.

While in the present instance the invention 45 has been described as used in connection with the purge-cap of a producer furnace, it is obvious that it may be used in other connections, such, for example, as 50 charging doors and the like.

What is claimed is:

1. In a gas producer furnace, a purge cap, a truck for supporting the same, a track upon which said truck is adapted to roll, means for receiving the wheels of the truck to prevent movement thereof along said track, and means for disengaging the wheels from said first-mentioned means to permit of the wheels rolling along said track, said last-mentioned means including a movable member associated with each of the track elements of said track and located in a position beneath the wheels, and fluid operated mechanism operable to move the movable members to elevate said truck and for subsequently moving said truck along said track. 55

2. In a gas producer furnace, a purge cap, a truck for supporting the same, a track upon which said truck is adapted to roll, 60 means for receiving the wheels of the truck to prevent movement thereof along said track, means for disengaging the wheels from said first-mentioned means to permit of the wheels rolling along said track, said last-mentioned means including a movable member associated with each of the track elements of said track and located in a position beneath the wheels, and means for elevating said members. 65

3. In a gas producer furnace, a purge cap, a wheeled truck for supporting the purge cap, a track upon which said truck is adapted to travel, means for receiving the wheels of the truck to prevent movement thereof along said track, a member associated with each of the track elements of said track and located in positions beneath the wheels, the lower edge of each of said members being irregular, a pair of rollers 70 in contact with the lower edge of each member so that upon movement of the members and by virtue of the irregular edges, said members may be raised, and mechanism operable to move said members to raise the 75 same to raise the truck vertically and to subsequently move said truck along said track. 80

EDWARD NELSON.
